Primary Examiner — Jonathan J Han*Assistant Examiner* — Jeff Leonard D Torres(74) Attorney, Agent, or Firm — Rumit Ranjit Kanakia(57) CLAIM

I claim the ornamental design for a belt, as shown and described.

DESCRIPTION

FIG. 1 is a Perspective view of a belt showing my new design;

FIG. 2 is a Top view thereof;

FIG. 3 is a Bottom view thereof;

FIG. 4 is a Left-side view thereof;

FIG. 5 is a Right-side view thereof;

FIG. 6 is a Back view thereof; and,

FIG. 7 is a Front view thereof.

The broken lines in the drawings depict portions of the belt that form no part of the claimed design.

1 Claim, 7 Drawing Sheets(56)
